(57) **CLAIM**

The ornamental design for an egg boiling tray, as shown and described.

DESCRIPTION

FIG. 1 is a top perspective view of an egg boiling tray, showing a first embodiment of our new design;

FIG. 2 is a bottom perspective view of FIG. 1;

FIG. 3 is a bottom plan view of FIG. 1;

FIG. 4 is a top plan view of FIG. 1;

FIG. 5 is an enlarged left-side elevational view of FIG. 1, the right-side elevational view, front elevational view, and rear elevational view all being identical thereto;

FIG. 6 is a cross-sectional view thereof, taken in the direction of line 6-6 in FIG. 4;

FIG. 7 is a top perspective view of a second embodiment thereof;

FIG. 8 is a bottom perspective view of FIG. 7;

FIG. 9 is a bottom plan view of FIG. 7;

FIG. 10 is a top plan view of FIG. 7;

FIG. 11 is an enlarged left-side elevational view of FIG. 7, the right-side elevational view, front elevational view, and rear elevational view all being identical thereto; and,

(Continued)

FIG. 12 is a cross-sectional view thereof, taken in the direction of line 12-12 in FIG. 10.
